UNITED STATES PATENT OFFICE.

PHILIP LUTZ, OF EAST NORTHPORT, NEW YORK.

BROOM HOLDER.

Application filed April 7, 1923. Serial No. 630,542.

To all whom it may concern:

Be it known that I, PHILIP LUTZ, a citizen of the United States, residing at East Northport, in the county of Suffolk and State of New York, have invented certain new and useful Improvements in Broom Holders, of which the following is a specification.

This invention relates to broom handles or tool holders and the like and more particularly to a novel and improved article of manufacture wherein a convenient device is provided for supporting the handle of a tool or implement as the case may be.

One of the objects of my invention is the provision of a broom handle or tool holder supporting device in the form of a clamp which permits the handle to be readily inserted therein and frictionally held thereby and adapted to be released from the device against the resistance of a spring so that a convenient and highly useful article of manufacture is provided capable for a multiplicity of uses.

Another object of my invention is the provision and construction of a tool holding device which may be stamped from metal, comprising a minimum number of parts, strong and durable, highly efficient in use, practical, easily manufactured and at a comparatively low cost, whereby its commercial possibilities are greatly enhanced.

I accomplish the above objects and others which will be more readily understood when taken in connection with the accompanying drawings showing a preferred embodiment thereof and wherein;

Figure 1 is a perspective view, showing the device connected to a wall and supporting a handle.

Figure 2 is a view partly in section of the clamp itself.

Figure 3 is a detail view of the spring connecting portion of the clamp.

Referring now to the drawings, wherein like reference characters designate corresponding parts throughout the several views, 5 designates in its entirety the attaching plate which is substantially rectangular in form and provided with apertures 6 for the passage of screws 7, whereby the device may be rigidly secured in horizontal position to a door or wall or on a workman's bench. The plate 5 is provided with an angularly disposed outwardly bent portion 8 of a reduced width, being further provided with

inwardly extending ears 9. The reduced portion 8 is formed preferably integral with the outwardly curved portion 10 of the plate which terminates in a lip 11 as clearly shown by Figures 1 and 2 of the drawings.

A resiliently held curved plate or clamping arm 12 of a shape to conform with the curvature of the portion 10 is provided, said plate 12 having also inwardly extending ears 13 which overlap the ears 9 and are connected thereto by the rivet 15, a resilient spring 16 on the rivet and disposed between the ears 9 is provided, one end of the said spring bearing against the plate 5 and the opposite end against the end of the movable plate 12 so that the clamp is normally closed. It will thus be seen that when a broom handle or tool is pressed against the lip 11 and the lip 12^a of the plate 12, 75 the said plate 12 will move outwardly against the resistance of the spring and consequently permit the insertion of the broom handle or tool as the case may be. On the other hand, by forcing the handle outwardly against the resistance of the spring, the plate 12 will fly outward and consequently release the handle.

It will thus be seen that from the above construction, I have provided a highly efficient and very simple clamping device which consists practically of but four parts which can easily be assembled and permits of the manufacture of large quantities at an extremely low cost.

While I have illustrated and described my invention with some degree of particularity, I realize that in practice various alterations therein may be made. I therefore reserve the right and privilege of changing the form of the details of construction or otherwise altering the arrangement of the correlated parts without departing from the spirit of the invention or the scope of the appended claims.

Having thus described my invention what I claim as new and desire to secure by United States Letters Patent is:—

1. A handle or tool supporting device comprising a plate attachable to a wall or support, a curved arm formed with the said plate and disposed at an angle thereto, inwardly struck ears at the juncture of the plate and arm, and a resiliently held clamping plate cooperating with the curved arm to frictionally retain the handle or tool.

2. A handle or tool supporting device

comprising a plate attachable to a wall or support, a curved arm formed integral therewith and disposed at an angle thereto, inwardly struck ears at the juncture of the plate and arm, a clamping arm conforming to the shape of the first mentioned curved arm, ears formed at the inner end of the

clamping arm overlying the ears of the curved arm, a rivet connecting the said ears and a spring on the rivet to normally maintain the clamping arm in its closed position.

In testimony whereof I affix my signature.
PHILIP LUTZ. [L. s.]
